UNITED STATES PATENT OFFICE.

WILLIAM O. STOKES, OF NEW YORK, N. Y.

CARBURETER.

1,289,300.

Specification of Letters Patent. Patented Dec. 31, 1918.

Application filed March 11, 1916. Serial No. 83,493.

To all whom it may concern:

Be it known that I, WILLIAM O. STOKES, a citizen of the United States, residing at New York, in the county of Bronx and 5 State of New York, have invented certain new and useful Improvements in Carbureters, of which the following is a full, clear, and exact specification.

This invention relates to carbureters, and 10 has for its object to combine with an ordinary single jet or multiple carbureter an auxiliary carbureter which is especially intended for facilitating the starting of the combustion engine, and also enabling the engine to run idly at a lower speed than is 15 possible with the ordinary carbureter, and also assisting the ordinary carbureter to produce a better vaporization of the liquid fuel.

20 Ordinary single jet carbureters are expected to vaporize the fuel under too wide a range of operating conditions. That is, the air passage has to be of sufficient size to feed the engine at the maximum speed, and 25 under such conditions the air velocity past the fuel nozzle, which is a function of the vacuum on the fuel nozzle caused by the engine suction, is such as to more or less satisfactorily vaporize the fuel. However, 30 when the engine is throttled down, as by an ordinary butterfly or sliding throttle in the mixing chamber above the fuel nozzle, the air velocity at the fuel nozzle becomes so low, and the vacuum so slight, very little 35 fuel is vaporized. Even if the vacuum be strong, and the air velocity past the fuel nozzle low, the only result is to draw the fuel from the nozzle in drops instead of in atomized particles. It, therefore, results 40 that in order to secure any vaporization at low speed, ordinary single jet carbureters are uneconomical at high speed, because they supply too much fuel. Moreover, when it is attempted to thin out the air at high speed 45 by means of automatic air valves, the low speed conditions are not bettered, because there is still the defect of not having sufficient air velocity at the fuel nozzle to properly atomize the fuel.

50 The above defects have induced the provision of various arrangements for priming the engine at low speed, such for example as injecting fuel into the top of the manifold, but these are not reliable, and are ineffective 55 when the temperature is very low.

By this invention, an auxiliary carbureter

is provided, which is connected at the fuel end to the float chamber of the ordinary carbureter, and has its mixing chamber connected to the engine manifold above the ordinary throttle, and above the main fuel nozzle. The engine is now started solely on the auxiliary carbureter, with the main throttle entirely closed, the result being 60 that the entire vacuum of the engine is directed across the auxiliary fuel nozzle, even at low hand cranking speed, resulting in a certain vaporization of the fuel and much quicker and better starting of the engine, even at very low temperature. To facilitate 65 the starting, the auxiliary carbureter is provided with a manually controllable needle valve which can be opened at the moment of starting to permit a freer flow of fuel so as to form a relatively rich mixture, 70 the needle valve then closing automatically to the predetermined running position sufficient to form a proper mixture to maintain the engine at idling speed. An automatic air valve is also provided which will become 75 effective at the idling speed of the engine to properly thin out the mixture. As the engine speeds up and the throttle is opened to increase the power, the auxiliary carbureter is always operative, and enables 80 the main carbureter to be set for a thinner mixture than is otherwise possible. The result is that by the combination of the main and the auxiliary carbureters a much more powerful mixture is obtained and there is a decided economy of fuel.

In actual practice, it has been found that this invention is advantageous in that fuel is saved, starting either by crank or by power 85 starter is more certain, and more power is obtained from an engine equipped with this invention than one equipped simply with a stock carbureter.

In the accompanying drawings, Figure 1 is a section of a carbureter embodying the invention;

Fig. 2 shows a simplified modification of the auxiliary carbureter, and

Fig. 3 shows an additional modification applicable to Figs. 1 and 2.

105 1 represents the intake manifold of the engine, 2 the gasoline supply to float chamber 3 through valve 4 controlled by float 5, and 6 is the fuel nozzle controlled by needle valve 7 and located in the air passage 8. 9 110 is an auxiliary air inlet which is controlled by an air valve as 10 located in the mixing

chamber 11 below the throttle 12. The foregoing parts are all of usual construction, and may be modified in accordance with well known practice.

14 is a liquid fuel pipe tapped into the side of float chamber 3 and leading to an auxiliary fuel nozzle 15. 16 is a float valve having angular or grooved sides and adapted to be moved by the flow of liquid at 10 high speed to practically throttle the fuel outlet 15. 17 is a screw for adjusting the position of float 16. Valve 16, in Fig. 1, is for the purpose of opening and closing nozzle 15. At a very low engine speed with 15 throttle closed as in cranking, this valve drops, admitting more fuel, the quantity determined by adjusting screw 17, without decreasing the volume of air and also compensates, according to the opening of throttle 12 in main carbureter. When throttle 20 12 is closed, valve 16 is drawn closed at idling speed of motor. When throttle 12 opens, permitting a flow of fuel from nozzle 6, with the proportion of air that is necessary 25 for the proper mixture, valve 16 remains closed, until throttle 12 is opened about half way. After that point of opening, the vacuum decreases in the manifold 1 above throttle 12, also decreasing the vacuum 30 in pipe 30. Therefore, the vacuum at nozzle valve 15, that holds 16 to its seat, is reduced allowing more fuel to enter through pipe 30, which permits more fuel to pass to the weakened mixture from large 35 carbureter. This is quite necessary to get an economical, homogeneous and powerful mixture. As all carbureters are set for the proper mixture, with a small opening of throttle, say a quarter to a half opening, 40 the mixture will weaken when throttle passes half opening which decreases power and causes preignition unless it is somewhat enriched, as just described. Where such refinement of liquid fuel flow is not desired, 45 the screw 17 may be turned up so as to cause the float 16 to entirely cut off the fuel nozzle 15. The starting fuel nozzle 18 is supplied with fuel from the pipe 14, and is controlled by needle valve 19 having a 50 screw-threaded shank 20 threaded into the casing 21. The screw 20 is provided with a lever arm 22, which is split and can be clamped to the screw 20 by screw 23. 24 is a spring having one end attached to the 55 lever 22 and the other end to the casing 21 tending to turn the screw 20 down into the casing to close the needle valve 19. 25 is a stop on the opposite end of arm 22 which contacts with the casing to limit the closing 60 movement of the needle valve 19. By loosening the screw 23, while the stop 25 is against the casing, the screw 20 can be adjusted in or out to give the proper needle valve opening. This is determined by running 65 the engine and adjusting the needle

valve until the proper mixture is obtained, the main throttle 12 at this time being closed. Ordinary throttles 12 usually are cut out so as to leave some slight opening at all times through the mixing chamber, but better results are obtained with this invention if the throttle is caused to completely shut off the main fuel nozzle 6 when closed. This, however, is not essential. The arm 22 is connected by a link 27 either to the dash, where 70 the engine is equipped with a self starter, or to the front where the engine is to be cranked by hand. Both connections may be used so that the needle valve can be controlled whichever mode of starting is used. 75 28 is the air inlet for the auxiliary carbureter which is controlled by air valve 29 and the mixture passes through the mixing pipe 30 to the inlet manifold above the throttle 12. Valve 29 is for the purpose of 80 controlling vacuum and regulating volume. 32 is an auxiliary air inlet for the auxiliary carbureter which is controlled by a spring pressed angular valve 33, the tension of the spring being adjusted by nut 34. Air valve 85 33, is for the purpose of controlling the vacuum and admitting more air into manifold. Valve 33 is made of regular polygons of stock which prevents valves from sticking or becoming clogged. This auxiliary 90 air inlet valve 33 is adjusted so that it does not open when the engine is being cranked, either by hand or by the starter, but when the engine is running idly, its speed is sufficiently increased to produce sufficient vacuum so as to slightly open valve 33. This thins out the mixture to the proper degree so as to produce even and powerful explosions in the engine cylinders. The lever 22 95 is only actuated momentarily as the engine 100 pistons begin to move, so as to let the liquid fuel flow freely through nozzle 18 while nozzle 15 is closed. Owing to the relatively small size of pipe 28 and the high air velocity across the fuel nozzle 18, the action is 105 similar to that of an atomizer, and the fuel is strongly atomized and thoroughly mixed with the air before it reaches the engine cylinder. 36 is a set screw for clamping the nut 34 in adjusted position. 110 115

In Fig. 2, like parts are similarly numbered, the difference being that the device is more condensed, and the float valve 16 and its nozzle 15 are eliminated. 36 is a set screw for holding the air valve 29 in this figure in adjusted position. In Fig. 1 the air valve 29 stays adjusted by its friction.

In Fig. 3, a modification is shown in which the arm 22 is coupled by link 28 to arm 39 of air valve 29, so that when the needle valve 19 is opened the air valve 29 is partly closed, cutting down the initial air and producing a somewhat richer mixture and easier starting.

From the foregoing description, it is thought that the operation of the device can 130

be clearly understood. It will be seen that in operation, there will always be some vacuum through the auxiliary carbureter even with the main throttle wide open, and this will 5 produce a powerful mixture upon a minimum quantity of fuel. As the main throttle 12 is closed, the vacuum becomes stronger through the auxiliary carbureter and thereby produces a better mixture than can be produced 10 by the main carbureter at low speed. The small carbureter produces ample mixture to both start the engine, and to allow it to idle, and in practice where this invention has been applied to a stock carbureter it has 15 been found that the engine will start easier, and idle at a much lower speed than was possible by the stock carbureter alone. This is a feature of decided advantage owing to the present trend toward high speed engines, because 20 it has been found that many of these engines do not idle well with the ordinary stock carbureter unless at a rather high speed. When equipped with this invention a much lower idling speed can be secured 25 without galloping or jumping, or flooding of the carbureter. At running speeds, where the engine is developing power, a greater drive at low speed is produced because of the better and more homogeneous mixture.

30 Various modifications and changes may be made in the detailed construction herein shown without departing from the scope of the appended claims.

Having thus described my invention, I declare that what I claim as new and desire to secure by Letters Patent, is:—

1. An auxiliary carbureter for attachment to a main carbureter, said auxiliary carbureter being of low capacity for starting and 40 idling and being inversely effective according to the opening of the main engine throttle, comprising a casing having a fuel inlet containing a fuel nozzle, an air inlet, a mix-

ing passage extending from said nozzle to the main carbureter mixing passage, a needle 45 valve in said fuel nozzle having a closing spring, adjustable means for limiting the closed position, and means controllable from a distance for opening said needle against the spring, said needle valve returning to its 50 adjusted open position when released.

2. An auxiliary carbureter for attachment to a main carbureter, said auxiliary carbureter being of low capacity for starting and idling and being inversely effective accord- 55 ing to the opening of the main engine throttle, comprising a casing having a fuel inlet containing a fuel nozzle, an air inlet, a mixing passage extending from said nozzle to the main carbureter mixing passage, an aux- 60 iliary air inlet having an automatic air valve, a needle valve in said fuel nozzle having a closing spring, adjustable means for limiting the closed position, and means controllable from a distance for opening said needle 65 against the spring, said needle valve returning to its adjusted open position when released.

3. In combination with a main carbureter comprising a float chamber, fuel nozzle, mixing passage, auxiliary air inlet, and throttle, a flow controlled fuel throttling valve in the fuel nozzle, and an auxiliary low capacity carbureter connected between said float chamber and said mixing passage beyond 75 said throttle, said auxiliary carbureter having an air inlet to its fuel nozzle, a spring closed needle valve therein, and an adjustable stop for limiting the closing of said valve so that it closes from wide open position to a predetermined open running position. 80

In testimony whereof I affix my signature, in presence of two witnesses.

WILLIAM O. STOKES.
